GYRATORY CRUSHER

Siegfried Kieskalt, Frankfort-on-the-Main-Hochst, Germany, assignor to I. G. Farben-industrie Aktiengesellschaft, Frankfort-on-the-Main, Germany

Application October 2, 1936, Serial No. 103,776
In Germany October 5, 1935

5 Claims. (CL. 83—10)

The present invention relates to a gyratory crusher and more particularly to a gyratory crusher which may freely oscillate in the interior of a crusher bowl.

5 I have found that when the upper part of the crusher head of a conical crusher caused to perform circular or substantially circular oscillations by a rapidly rotating unbalanced body is suspended from a rigid body by non-elastic means 10 or means which have little elasticity, great efficiency of operation is attained. The oscillating crusher head acts in this case, by pressure, on the small pieces of the material introduced between said crusher head and the crusher bowl, whereas large flat pieces are crushed by bending stress. The rapidly rotating unbalanced body is directly coupled with the driving motor, preferably by way of an elastic coupling, and gearing becomes unnecessary in the arrangement according 15 to the invention, so that frictional loss can be limited as far as possible. The crusher head may be suspended by using for instance wire ropes, chains, leather bands and other means of this kind. All these means are characterized by the fact that they are not stiff against transversal movements to any side. A high degree of reliability with little risk of breakage occurs in arrangements embodying the invention, because, though heavy duties are called 20 for complete flexibility is provided. This is particularly the case if the suspending means have no or very little lateral rigidity. By the merely oscillatory (not rotating) motion of the crusher head the danger of smearing or plastering is overcome and consequently the crusher may be caused to oscillate at frequencies varying, depending on the kind of the material to be crushed, from about some hundreds to about some thousands per minute so that a considerable 25 increase of the quantity of crushed material is attained as compared with that hitherto attainable. Depending on whether the greatest effect of the crusher is to be produced in the mouth or in the lower part of the apparatus the unbalanced body may be mounted at the upper or lower part of the crusher head; in this case it is advisable to locate a heavy mass at the part of the crusher head axially remote from the unbalanced body, in order to prevent the remote 30 part of the crusher head from oscillating to a marked extent. Where it is desired to attain the same effect at the mouth and in the lower part of the apparatus the effect of the unbalanced mass is distributed along the length of the crusher head so that all parts of the crusher head

make circular oscillations about its longitudinal axis.

Figures 1 to 3 of the accompanying drawing diagrammatically illustrate the invention by way of example, each of the figures being a vertical section.

Fig. 1 illustrates a crusher producing its greatest effect at the mouth of the apparatus, Fig. 2 illustrates a crusher producing its greatest effect in the annular opening at the lower part of the apparatus and Fig. 3 illustrates a crusher producing substantially equal effects at the mouth and at the outlet.

The crusher illustrated in Fig. 1 where the greatest effect is produced at the mouth mainly comprises a crusher head *a* suspended somewhat like a pendulum in the interior of the crusher bowl *f* by slightly elastic or non-elastic means *b* for instance wire ropes, chains or leather bands. The unbalanced eccentric body *c* which is mounted in the upper part of the crusher head is coupled by means of an intermediate shaft *d* with the driving motor *e* mounted in the bottom part of the crusher head. This bottom part of the crusher head is heavily formed to provide a heavy mass *g* in order that when the rapidly rotating unbalanced mass *c* is driven the upper part of the crusher head is caused to oscillate much more vigorously than the bottom part which may not oscillate at all.

The crusher illustrated in Fig. 2 which produces its greatest effect at the annular opening at the lower part of the apparatus mainly comprises the crusher head *a* which is suspended in the interior of the crusher bowl *f* somewhat like a pendulum on slightly elastic or non-elastic means *b*. The unbalanced body *c* is mounted in the bottom part of the crusher head *a* and the heavy mass *g* is located at the upper part of the crusher head; this unbalanced body *c* is coupled with the driving motor *e* by an intermediate shaft *d* and an interposed ball and socket joint *i*. On driving when the unbalanced body *c* is rotated it causes the lower part of the crusher head to vigorously oscillate, the amplitude of the oscillations decreasing towards the upper part by reason of the effect of the heavy mass *g*.

Fig. 3 is a cross section of a device having a substantially equal effect at the mouth and at the outlet. Here also the crusher head *a* is suspended in the interior of the crusher bowl *f* on slightly elastic or non-elastic means *b*. Unbalanced bodies *c* are arranged and situated along the length of the crusher head and are coupled with the driving motor *e* by means of an elastic

coupling *h*. The action of the bodies *c* in this case is distributed along the entire longitudinal axis of the crusher head *a*. When the unbalanced bodies are driven a vigorous circular oscillation of all parts of the crusher head *a* takes place about its longitudinal axis so that the same effect is produced at the mouth and at the opening at the bottom of the apparatus.

I claim:

- 10 1. In a gyratory crusher of the type comprising a crusher bowl and a crusher head having generally upright cooperating crushing surfaces, elongated flexible means connected to the crusher head and arranged to suspend the same and movable in relation thereto during operation of the crusher to various relative angular positions with respect to the axis of the head, said head having an out of balance weight in its interior for exciting oscillations and means for rotating the out of balance weight.
- 15 2. In a gyratory crusher of the type comprising a crusher bowl and a crusher head having generally upright cooperating crushing surfaces, elongated flexible means connected to the crusher head and arranged to suspend the same and movable in relation thereto during operation of the crusher to various relative angular positions with respect to the axis of the head, a heavy mass mounted in the upper part of the crusher head and an out of balance weight rotatable in the bottom part of the crusher head around its fixed axis and means for rotating the out of balance weight.
- 20 3. In a gyratory crusher of the type comprising a crusher bowl and a crusher head having generally upright cooperating crushing surfaces, elongated flexible means connected to the crusher head and arranged to suspend the same and movable in relation thereto during operation of the crusher to various relative angular positions with respect to the axis of the head, said head having in its interior a heavy mass at one end and an out of balance weight at the opposite end and means for rotating the out of balance weight.
- 25 35 3. In a gyratory crusher of the type comprising a crusher bowl and a crusher head having generally upright cooperating crushing surfaces,

elongated flexible means connected to the crusher head and arranged to suspend the same and movable in relation thereto during operation of the crusher to various relative angular positions with respect to the axis of the head, a heavy mass mounted in the bottom part of the crusher head and an out of balance weight rotatable in the upper part of the crusher head around its perpendicular axis and means for rotating the out of balance weight.

4. In a gyratory crusher of the type comprising a crusher bowl and a crusher head having generally upright cooperating crushing surfaces, elongated flexible means connected to the crusher head and arranged to suspend the same and movable in relation thereto during operation of the crusher to various relative angular positions with respect to the axis of the head, said crusher head having two rotatable out of balance weights in its interior, one at the upper and one at the lower part and means for rotating the out of balance weights.

5. In a gyratory crusher of the type comprising a crusher bowl and a crusher head having generally upright cooperating crushing surfaces, elongated flexible means connected to the crusher head and arranged to suspend the same and movable in relation thereto during operation of the crusher to various relative angular positions with respect to the axis of the head, said crusher head having in its interior a heavy mass at one end and an out of balance weight at the opposite end and means for rotating the out of balance weight.
